UNITED STATES PATENT OFFICE.

EDWIN G. BUSSE AND GEORGE N. VAN SWERINGEN, OF CHICAGO, ILLINOIS, ASSIGNEES
TO CHICAGO RAILWAY EQUIPMENT COMPANY, OF CHICAGO, ILLINOIS, A CORPO-
RATION OF ILLINOIS.

BRAKE HEAD.

Application filed January 19, 1920. Serial No. 352,521.

To all whom it may concern:

Be it known that we, EDWIN G. BUSSE, and GEORGE N. VAN SWERINGEN, citizens of the United States, residing at the city of Chicago, county of Cook, and State of Illinois, have invented a certain new and useful Improvement in Brake Heads, of which the following is a full, clear, and exact description, such as will enable others skilled in the art to which it appertains to make and use the same, reference being had to the accompanying drawings, forming part of this specification, in which—

Figure 1 is a side elevational view of our improved brake head.

Figure 2 is a detail view of one of the renewable wearing surfaces.

Figure 3 is a detail view of another form of renewable wearing surface.

Figure 4 is a side elevational view of the brake head provided with different forms of renewable wearing surfaces.

Figure 5 is a front elevational view of the form shown in Figure 4.

Figure 6 is a side elevational view of a modified form of brake shoe having renewable lugs.

Figure 7 is a partial front elevational view of the form shown in Figure 6.

This invention relates to a new and useful improvement in brake heads in which the lugs or the wearing surfaces thereof are made renewable. When a brake beam is improperly mounted, the brake shoe wears unevenly oftentimes wearing away entirely at top and bottom and wearing into the toes or lugs of the brake head; also, if the fit between the brake head and brake shoe is not close there is more or less play or lost motion between the shoe and head, which increases with the length of service frequently to the extent of wearing away the toes or lugs. It is the practice with certain railroads when such condition arises to weld an additional wearing piece on the head to replace the toe or lug which has been worn or ground off. In many cases, the top and bottom toes only are worn or rubbed away, leaving the balance of the head in perfect condition.

It is the purpose of the present invention to lengthen the life of the brake shoe head by providing it with individual renewable

and removable wearing surfaces which may form part of or the entire toe or lug of the brake head. This wearing strip, toe or lug can be made of wrought metal, hardened steel or cast iron as found most desirable, the important feature of the invention being that it is removable and replaceable when worn.

In the drawings, 1 indicates a brake head of a well known form, and in Figure 1 we have shown the lugs or toes faced with hardened steel plates 2 riveted in position by rivets 3.

In Figure 3 is shown a locking lug 5 by which the hardened steel wearing surface may be interlocked with the lug or toe of the brake head.

In Figures 4 and 5, the renewable wearing surface 6 is provided with a projection 7, by which it is attached to the lug of the brake head by means of a rivet 8, whereas in Figures 6 and 7 the entire toe or lug 9 is removable and renewable, the same being preferably provided with a dovetail interlocked with the brake head and held in position by means of a rivet 10.

What I claim is:

1. A brake head comprising a body integral from end to end, and individually renewable shoe supporting elements independently secured to said body.

2. A brake head comprising a body adapted to extend throughout the length of the brake shoe and integral from end to end and provided with renewable shoe supporting elements at intervals along its surface.

3. A brake head comprising a body having a portion adapted to be mounted on the end of a brake beam and having integral extensions which are provided along their faces with undercut recesses spaced at substantial intervals, and renewable undercut lugs adapted to fit in said recesses and to support and space a brake shoe from said body.

4. In a break head, an integral body adapted to be rigidly mounted upon a brake beam, and renewable shoe supporting elements provided with a bearing on said body and adapted to transmit braking stresses directly to said body perpendicularly to the bearing surfaces of said body and elements.

5. In a brake head, a beam attaching body portion having substantial integral exten-

sions, renewable shoe supporting lugs at opposite ends thereof, and renewable shoe supporting lugs intermediate said first-mentioned lugs.

5 6. A brake head comprising a body, and relatively short individually renewable shoe supporting elements independently mounted

on and secured to said body adjacent to the point at which they support the shoe.

In testimony whereof we hereunto affix 10 our signatures this eighth day of December, 1919.

EDWIN G. BUSSE.
GEORGE N. VAN. SWERINGEN.
